[57] **CLAIM**

The ornamental design for a dual compartment bottle or similar article, substantially as shown and described.

DESCRIPTION

FIG. 1 is a side elevational view of a dual compartment bottle or similar article embodying my new design, the opposite side being the same in appearance;

FIG. 2 is a view looking from the right of FIG. 1, the opposite side being the same in appearance;

FIG. 3 is a top plan view; and

FIG. 4 is a bottom plan view thereof.
